UNITED STATES PATENT OFFICE

2,438,605

ELECTRICAL THERAPEUTIC DEVICE

Fred J. Hart, Salinas, Calif., assignor of one-half
to College of Electronic Medicine, San Fran-
cisco, Calif., a corporation of California

Application September 12, 1945, Serial No. 615,858

1 Claim. (Cl. 128—419)

1 My invention relates to improvements in elec-
trical apparatus for therapeutic treatment.

One object is the provision of such a device
adapted to direct alternating magnetic lines of
force into body tissues for therapeutic use.

Another object is the provision for chopping
such alternating fields at short intervals.

A further object is the provision of means for
producing an inhomogeneous alternating mag-
netic field for therapeutic use.

A still further object is the provision of means
for producing surging electrical energy in high
frequencies for therapeutic use, and with each
train beginning with comparatively high inten-
sity then damped out quickly with a rest
period before the next wave train.

Other objects will be apparent from the follow-
ing description and accompanying drawings, in
which:

Figure 1 is a diagrammatic view of a device
embodying my invention.

Figure 2 is a similar view but indicating a
different form of electrical switch operating
mechanism.

Figure 3 indicates a cathode ray oscillograph
pattern of one train of energy curves produced
by my device.

Figure 4 is a longitudinal view with an electro-
magnet and casing shown in section and the elec-
trical circuit in diagram, and

Figure 5 is a front elevation of the device of
Figure 4.

Referring more particularly to the drawings I
provide an electro-magnet made up of a core 6
and a coil 7. The core 6 may be of soft iron or
a suitable magnetic alloy. It preferably has a
short cylindrical portion at one end and an en-
larged bell-shaped portion at the other (see Fig-
ure 4). The coil 7 is disposed on said cylindrical
core portion with its length approximately that
of the cylindrical core portion and its diameter
substantially that of the bell-shaped portion.

The coil 7 is connected in series with a con-
denser 8 and the primary coil 9 of a transformer
to provide an oscillatory circuit. The secondary
coil 10 of said transformer is connected through
a small condenser 11 to one terminal of the pri-
mary transformer coil 9. A treatment electrode
12 is connected to the transformer coil 10 at the
opposite terminal from the condenser 11 con-
nection, and disposed in front of the cylindrical
part of core 6 in the strongest part of the mag-
netic field of said electro-magnet (see Figures 4
and 5).

The device is provided with electrical supply

wires 13 and 14. I preferably provide a switching
mechanism in each of said wires 13 and 14, as
illustrated, but in some instances only one of
the switching mechanisms may be desired.
5 When one switching mechanism is used, it may
be in either wire 13 or wire 14. When both
switching mechanisms are used they should be
closed and opened simultaneously.

In one of these switching mechanisms a fixed
10 contact 15 is connected with the wire 13 and a
movable contact 17 mounted on a swinging
arm 18. The latter is connected by wire 19 to a
convenient point of the oscillatory circuit be-
tween coil 9 and condenser 8. A fixed contact
15 is connected to wire 14 and adapted to be
engaged by a movable contact 20 on a swinging
arm 21. The latter is connected to a suitable
point of said oscillatory circuit between coil 7
and condenser 8.
20 Any desired means may be provided to operate
said switching mechanisms.

In Figure 1, I have indicated a motor 23 of
conventional design connected across wires 13
and 14 for continuous operation while the device
25 is in use. The motor 23 is connected through
any desired reducing gear to operate a cam mem-
ber 24. I have illustrated a reducing gear made
up of a suitable belt 25 and pulleys 26 and 27.
The cam member 24 is provided with any de-
30 sired number of cams 28 adapted to engage suit-
able cams 29 on swinging arms 18 and 21 so that
switch points 17 and 20 will engage and disen-
gage the fixed switch points 15 and 16 simul-
taneously. A resilient member 29' is shown con-
necting the swinging arms 18 and 21 to hold the
cams 28 in operating relation to cams 29.

In Figure 2, I have indicated a different means
for operating the switching mechanisms. In this
form a solenoid coil 30 is provided with a longi-
40 tudinally moving core 31 with an enlargement 32
adapted to engage swinging arms 18 and 21
simultaneously. A thermally operated switch is
adapted to control the operation of the solenoid
30. This device is of conventional design and
45 provided with an arm 33 of two metals of differ-
ent thermal coefficients so that when said arm is
cold a switch point 34 mounted on it will engage
a fixed switch point 35 and permit the flow of
50 current between wires 13 and 14 through wires
36, contacts 34 and 35, arm 33 and the solenoid
coil 30.

At the same time a current will flow through
a resistance wire 37 attached to the arm 33 and
wound around an insulator 38 on said arm 33
55 and finally connected to one of wires 36. As soon

as current has heated coil 37 and arm 33 the latter will be moved to disconnect points 34 and 35 to break the current permitting coil 37 and arm 33 to cool again. This cycle is repeated again and again as long as the device is in operation.

While the electrical current is broken through points 34 and 35, resilient members 39 will move the solenoid core 31 and swinging arms 18 and 21 to disconnect switch points 17 and 20 from fixed points 15 and 16 thereby cutting off the current to the oscillating circuit.

The core 6 is mounted in a housing 40 of any desired shape and size, such as by a plurality of brackets 41 and screws 42. The front of the housing 40 is open for access to the operating parts. This opening is closed by a removable covering 43 of glass or other desired material and held in place by a bezel 44 and screws 45. A lining of asbestos 46 may be placed on the inside of covering 43 when desired. The arrangement of the parts is such that a narrow space 47 provides an air column between in front of the coil 7 and core 6 and back of lining 46. The housing 40 may be provided with as many ventilating holes 48 as desired.

The housing 40 is provided with trunnions 49 which engage openings in the upper ends of the supporting members 50 and 51. Knurled nuts 52 are threaded on said trunnions 49 and adapted to lock the supporting members in operative condition.

The transformer made up of coils 9 and 10 is preferably mounted at the center on the back of core 6 with condensers 8 and 11 at the sides of the transformer. The switches and switch operating means may be mounted in any desired manner, such as on the back of core 6 and as close to the latter as possible in order to be in the strongest magnetic field.

An "off" and "on" switch 53 is provided in wire 14 for controlling an alternating electrical current to the device.

The device is intended for operation on alternating electrical currents of the voltages and frequencies used in the usual house lighting currents. An electromagnet operated on such a current produces an alternating magnetic field. An electrical conductor in such a field will have electrical currents set up in it, hence body tissues disposed adjacent covering 43 will have electrical currents set up in them. Since body tissues are easily penetrated by magnetic fields this provides an efficient means of introducing electrical currents to them.

During the times switch points 17 and 20 are in contact with the points 15 and 16 current flows to the magnetic coil 7 and sets up a magnetic field around such coil and core 6. A cathode ray oscillographic pattern of the electrical current set up in body tissues in this magnetic field is indicated at 54 in Figure 3.

When the house current is cut off any current

in coil 7 at the instant, and any current set up in this coil due to the collapsing of said magnetic field is caused to oscillate through the circuit made up of coils 7 and 9 and condenser 8. This oscillatory energy is highly damped out and is indicated by the pattern 55 in Figure 3.

This damped oscillatory energy is led to electrode 12 through the inductive coupling between coils 9 and 10 and through the capacity coupling of condenser 11.

Thus, while an alternating house current is flowing through coil 7, electrical energy such as indicated by pattern 54 is induced in the patient and at the instant of breaking such current a highly damped oscillatory electrical energy indicated in pattern 55 is led to the patient. Each making and breaking of the house current produces a train of patterns 54 and 55 with a distinct rest to the tissues before the next cycle begins.

Because of the particular form of core 6, the magnetic field at the front of the device will be most intense at electrode 12 and become gradually weaker toward the periphery of the covering 43. This difference in field strength produces an inhomogenous magnetic field and will set up Foucault currents in body tissues adjacent to the front covering 43.

I claim:

30 A device of the class described comprising an oscillation circuit including a capacitor and an inductor with the latter providing an electromagnet, two alternating current supply wires connected with said oscillation circuit, a switch connected in each supply wire, operating means connected with said switches adapted to operate the latter concurrently so that a magnetic field is set up around said electromagnet while said switches are closed and both of said supply wires are cut free from said oscillation circuit while said switches are open, a treatment wire connected to said oscillation circuit and adapted to receive electrical energy trapped in said oscillation circuit at each opening of said switches and a condenser in said treatment wire adapted to limit the flow of electrical current to said treatment wire while said switches are closed.
